Term of patent 14 years

(Cl. D58—5)

FIG. 2

FIG. 1

FIG. 3

FIG. 4

FIGURE 1 is a side elevational view of a jug showing my new design;

FIGURE 2 is a top elevational view thereof;

FIGURE 3 is the front plan view thereof; and

FIGURE 4 is the back elevational view thereof.

The side not shown is the same as the side shown. The characteristic features of this design reside in the configuration shown in full lines on the drawings.

I claim:

The ornamental design for a jug, substantially as shown and described.
